UNITED STATES PATENT OFFICE

2,056,148

GRINDING WHEEL TRUING APPARATUS

Carl G. Flygare, Worcester, Mass., assignor to
Norton Company, Worcester, Mass., a corpora-
tion of Massachusetts

Application August 6, 1935, Serial No. 34,940

11 Claims. (Cl. 125—11)

members (not shown) which are old and well-known features in a grinding machine such as, for example, that shown in the prior Norton Patent No. 762,838 dated June 14, 1904. The head and footstock have not been illustrated in the present case, since they are not considered part of the present invention. A rotatable grinding wheel 16 is rotatably mounted in the usual manner on a transversely movable wheel slide (not shown), for details of which reference may be had to the above-mentioned prior patent to Norton. 5 10

In the grinding of large rolls, such as used in a steel rolling mill which frequently weigh several tons, it is desirable to provide a truing apparatus which permits the truing of the operative face of the grinding wheel 16 while a roll or work piece 17 is supported in operative position on the table 14. It is desirable to provide a truing apparatus which may be readily positioned on the machine or removed therefrom for truing the operative face of the grinding wheel to present the desired surface for grinding. In the preferred construction, the truing apparatus is supported by a substantially U-shaped frame 20 which is arranged to straddle the roll or work piece 17. The U-shaped frame 20 is provided with a supporting pad 21 which serves to engage the work piece at a point adjacent to the line of grinding contact between the wheel 16 and the roll or work piece 17. 30

The truing tool end of the U-shaped frame 20 is provided with an outwardly extending boss 22 having a cylindrical aperture 23 arranged to receive a truing tool 24 in which is mounted a diamond or other truing medium 25. The holder 24 is held in adjusted position within the boss 22 by means of a screw 26, thus permitting the tool to be readily removed from the attachment or inserted therein or adjusted relative thereto.

The other end of the U-shaped frame 20 is arranged to be removably attached to a portion of the machine. In the embodiment of the invention illustrated, the U-shaped frame 20 is preferably removably attachable to the table 14 by means of a stud 28 which is mounted on a transversely movable slide 29. The slide 29 is supported on slideways 30 on a supporting frame 31. The slide 29 is provided with a nut 32 meshing with an adjusting screw 33 which is supported in a bearing 34 on the frame 31. The screw 33 is provided with an adjusting knob 35 mounted on its outer end which serves to rotate the screw 33 and through the nut 32 adjust the position of the slide 29 transversely relative to the table 14, the roll 17 and the grinding wheel 16. The frame 55

31 is provided with a dovetailed surface 36 which is arranged to mate with a correspondingly shaped dovetailed surface 37 on the swivel table 14. The frame 31 is clamped in adjusted position on the dovetail 37 by means of a pair of clamping gibs 40 and 41 which have surfaces 42 mating with a portion of the dovetail 37. The clamping gibs are held in place by means of screws 43 and 44 which pass through the clamping gibs 40 and 41 and are screw threaded into the frame 31.

In order that the truing apparatus may be readily inserted on the machine or removed therefrom after truing, it is desirable to provide a suitable readily detachable connection, such as the pivot pin 28 having end portions which are provided with slabbed-off surfaces 45 and 46. The frame 20 is provided with a cylindrical hole 47 of a diameter equal to the diameter of the stud 28 and its lower portion is provided with an opening 48 which is of a width slightly greater than the distance between the slabbed-off surfaces 45 and 46. When it is desired to remove the truing apparatus from the machine, the frame 20 may be rocked in a clockwise direction (Fig. 1) to swing the opening 48 into alignment with the slabbed-off surfaces 45 and 46, and the frame 20 may then be moved toward the right, as viewed in Fig. 1, and the entire assembly removed from the machine so that the grinding operation on the roll 17 may be resumed. After the grinding operation has continued and it is desired to again true the wheel, the frame 20 may be readily inserted in its former operating position with the pivot 28 supporting the end of the frame 20 and the pad 21 supporting the other end of the frame in operative position in contact with the roll 17.

In truing the operative face of the grinding wheel, it is desirable that the truing tool 25 engage the periphery of the grinding wheel at a point substantially in a horizontal plane passing through the axes of the wheel and work so that the truing tool passing across the face of the grinding wheel engages the wheel along the line of contact between the grinding wheel and the work piece. This is particularly desirable and necessary in truing a grinding wheel when a roll or work piece is being crowned, that is, when the periphery of the roll is ground to a surface other than a true cylinder. In the grinding of rolls for use in the rolling mills, it is frequently necessary to generate a crown, either the convex or concave, on the surface of the roll so that when the roll is put in operative use in the rolling mill under pressure, the deflection of the roll due to the pressure will roll work of the desired shape and form. If the machine is set up for grinding a true cylinder, the table 11 is reciprocated longitudinally while the swivel table 14 is clamped in rigid engagement therewith. In such a grinding operation, the periphery of the grinding wheel is trued to present a true cylindrical grinding surface.

When it is desired to set up the machine for a roll crowning operation, a forming or crowning attachment is provided for causing a relative swiveling movement between the longitudinally reciprocable table 11 and the swivel table 14 so that when the roll being ground is reciprocated longitudinally, the swivel table will be rocked about its pivot 15 so that the desired longitudinal curvature will be produced on the roll being ground. Such a mechanism has not been illustrated in the drawing, since it is not considered

a part of the present invention. For details of the operation of a mechanism of this type, reference may be had to the prior patent to Dunbar and Flygare No. 1,970,000 dated August 14, 1934. When the machine is operated for roll crowning, as above described, it is desirable that the diamond or truing tool 25 be mounted exactly on the line of centers between the wheel and work axis so that when the diamond is passed across the face of the wheel due to the traversing movement of table 11, any swiveling movement of table 14 will be transmitted to the diamond 25 so as to generate a curved face on the periphery of the grinding wheel.

In order that the truing tool 25 may be maintained in the proper adjusted position relative to the wheel and work axis regardless of the size of the work being ground, an adjustable work engaging and supporting shoe 50 is provided. The shoe 50 is pivotally mounted on a stud 51 which is in turn carried by a pair of guide rods 52 and 53. The rods 52 and 53 slide in holes 54 and 55 respectively in the frame 20. The upper end of the rods 52 and 53 are connected by a head 56 which serves to rotatably support a bearing 57 of a feed screw 58. The upper end of the screw 58 is provided with a knob 59 so that the screw may be readily rotated within the head 56. The screw 58 meshes or engages a threaded aperture 60 in the frame 20 so that when the knob 59 is turned to rotate the screw 58 within the threaded aperture 60, the shoe 50 will be adjusted vertically relative to the frame 20, as viewed in Fig. 1.

It will be readily apparent from the foregoing disclosure that by rotation of the knob 59, the path of the truing tool or diamond 25 relative to the work and wheel axes may be varied by vertically adjusting the position of the work engaging shoe 50.

In order that the truing tool 25 may be readily adjusted into its proper position for truing different sizes of rolls, an indicating device is provided which includes a graduated scale 65 formed on the rod 53. The upper surface 66 of the frame 20 serves as an index or zero reading. By adjusting the knob 59 so that the proper reading on the scale 65 coincides with the index surface 66 on frame 20, the position of the truing tool may be readily set, for any given size roll being ground, to coincide with the line of contact between the grinding wheel and work piece.

In the operation of the improved truing apparatus, the supporting frame 31 for the truing apparatus is preferably clamped in a fixed position on the swivel table 14 in transverse alignment with the pivot pin 15. When it is desired to true the periphery of the grinding wheel 16, the wheel 16 and work 17 are separated from each other by a distance sufficient to admit the truing apparatus by means of the cross feeding mechanism (not shown). The truing apparatus frame 20 is then lifted into position so that the opening 48 is aligned with the slabbed-off surfaces 45 and 46 and the frame is moved so that the pin 28 engages the cylindrical hole 47 and the frame 20 is then rocked in a counterclockwise direction so that supporting pad 50 rests in operative position on the upper surface of the work 17. The knob 59 is then adjusted for the size of roll being ground so that the diameter of the roll being ground as indicated on scale 65 coincides with the index surface 66 to position the diamond truing tool 25 on the line of contact between the

grinding wheel and the work piece. The operator then adjusts the knob 35 so as to move the slide 29 and frame 20 toward the right (Fig. 1) so that the supporting pad 21 engages the surface 5 of the roll adjacent the line of contact between the wheel and the roll to hold the frame 20 rigidly in its truing position. The table 11 may then be reciprocated either manually or by power by a suitable traverse mechanism (not shown), such as that shown in the prior patent to Norton above referred to. The grinding wheel may then be fed into truing position with relation to the diamond 25 and the table 11 traversed to pass the diamond 25 across the face of the wheel 16 until it is trued to the desired surface.

The truing attachment may then be readily removed from the machine by turning the knob 35 to cause the slide 29 and the frame 20 to move a slight distance toward the left (Fig. 1). The entire frame 20 may then be swung in a clockwise direction until the opening 48 is aligned with the slabbed-off surfaces 45 and 46, and the frame may then be moved toward the right to disengage the pin 28 from the aperture 47 of the frame 20.

It will thus be seen that there has been provided by this invention a grinding wheel truing apparatus in which the various objects hereinabove set forth together with many thoroughly practical advantages are successfully achieved.

As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

Having thus described my invention, what I claim as new and desire to secure by Letters Patent is:

1. A roll grinding machine of the type having a rotatable grinding wheel and a rotatable work support which are movable longitudinally and transversely relative to each other, and a truing apparatus comprising a substantially U-shaped frame, a truing tool adjustably positioned at one end of said frame, a work engaging shoe adjacent thereto, and a second work engaging shoe adjustably positioned on said frame and arranged to engage the work on its upper surface so as to adjust the position of the frame to vary the path of the truing tool relative to the grinding wheel.

2. A grinding machine of the type having a rotatable grinding wheel and a rotatable work support which are movable longitudinally and transversely relative to each other, and a truing attachment comprising a substantially U-shaped frame, a truing tool carried at one end of said frame, detachable connections between the other end of said frame and the machine, a work engaging shoe on the tool end of said frame arranged to engage the work at a point adjacent the line of contact between the wheel and work, and a second work engaging shoe adjustably positioned on said frame and arranged to engage the work on its upper surface so as to adjust the position of the frame to vary the path of the truing tool relative to the grinding wheel.

3. A grinding machine of the type having a rotatable grinding wheel and a rotatable work support which are movable longitudinally and transversely relative to each other, and a truing apparatus comprising a substantially U-shaped frame, a truing tool adjustably positioned at one

end of said frame, a work engaging shoe on the tool end of said frame arranged to engage the work at a point adjacent to the line of contact between the wheel and work, detachable connections between the other end of said frame and the machine, a second work engaging shoe adjustably positioned on said frame and arranged to engage the work on its upper surface so as to adjust the position of the frame to vary the position of the truing tool relative to the 10 grinding wheel and work axis, and an indicating device associated with said second shoe to readily adjust the position of said truing tool for a predetermined size work piece.

4. A grinding machine of the type having a 15 rotatable grinding wheel and a rotatable work support which are movable longitudinally and transversely relative to each other, and a grinding wheel truing apparatus therefor comprising a substantially U-shaped frame arranged to 20 straddle the work piece, a truing tool adjustably mounted on one end of said frame, a work engaging shoe on said frame adjacent to said truing tool which is arranged to engage the work at a point adjacent to the line of contact between the wheel 25 and work, a transversely movable slide, a detachable connection between the other end of said frame and the transversely movable slide, and means to adjust the position of said slide transversely relative to the table so as to maintain 30 the shoe in supporting contact with the work.

5. A grinding machine of the type having a rotatable grinding wheel, a longitudinally movable work supporting table, a rotatable work support thereon, and a truing apparatus therefor comprising a substantially U-shaped frame arranged to straddle the work piece, a truing tool adjustably mounted at one end of said frame, a work engaging shoe on said frame adjacent to the tool end thereof which is 40 arranged to engage the work at a point adjacent to the line of contact between the wheel and work, a detachable connection between the other end of said frame and the machine, means to adjust the position of said connection transversely 45 relative to the machine so as to maintain said shoe in operative supporting contact with the work, and an adjustable shoe mounted on said frame and arranged to engage the upper surface of the work to permit adjustment of the 50 frame to vary the position of the truing tool relative to the grinding wheel and work axis.

6. A grinding wheel truing apparatus for a grinding machine comprising a substantially U-shaped frame, a truing tool mounted on one end 55 of said frame, a supporting shoe on said frame adjacent to said tool, a supporting member arranged to be clamped on said machine, a transversely movable slide on said member, detachable connections between the other end of said 60 frame and the slide, and means to adjust the slide to maintain said shoe in an operative position.

7. A grinding wheel truing apparatus for a grinding machine comprising a substantially U- 65 shaped frame, a truing tool mounted on one end of said frame, a supporting shoe on said frame adjacent to said tool, a supporting member arranged to be clamped on said machine, a transversely movable slide on said member, 70 and detachable pivotal connections between the other end of said frame and said slide whereby the truing apparatus may be readily attached or detached before and after a truing operation.

8. A grinding wheel truing apparatus for a 75

grinding machine comprising a substantially U-shaped frame, a truing tool mounted adjacent to one end of said frame, a supporting shoe on said frame adjacent to said tool, detachable connections between the other end of said frame and the machine, a second supporting shoe adjustably mounted on said frame, and means including an indicating device arranged to adjust the position of said second shoe relative to said frame to accurately position the truing tool for truing the grinding wheel.

9. A grinding wheel truing apparatus for a grinding machine comprising a substantially U-shaped frame, a truing tool mounted adjacent to one end of said frame, a supporting shoe on said frame adjacent to the tool, a supporting member arranged to be clamped on said machine, and detachable connections between the other end of said frame and said member, a second supporting shoe which is interposed between said first shoe and the detachable connections, and means including an indicator to adjust the position of said second shoe relative to said frame to position the truing tool in a predetermined relation with the wheel and work to true the same on the line of grinding contact between the wheel and work piece.

10. A grinding wheel truing apparatus for a grinding machine comprising a substantially U-

shaped frame, a truing tool mounted on one end of said frame, a supporting shoe on said frame adjacent to said tool, a second supporting shoe adjustably mounted on said frame and arranged to adjust the position of said tool relative to the grinding wheel axis, a supporting member arranged to be clamped on said machine, a transversely movable slide on said member, detachable connections between the other end of said frame and said slide, and means to adjust the position of said slide to maintain said shoe in an operative position.

11. A grinding wheel truing apparatus for a grinding machine comprising a substantially U-shaped frame, a truing tool mounted on one end of said frame, a supporting shoe on said frame adjacent to said tool, a second shoe adjustably mounted on said frame, means including an indicating device to adjust the position of said second shoe relative to said frame to accurately position the truing tool, a supporting member arranged to be clamped on said machine, a transversely movable slide on said member, detachable pivotal connections between said slide and said frame, and means to adjust the position of said slide to maintain said shoes in operative position to support said tool.

CARL G. FLYGARE.
